SHOCK ABSORPTIVE PACKAGING

John L. Gretz, Milford, Conn., assignor, by mesne assignments, to The B. F. Goodrich Company, Akron, Ohio, a corporation of New York

Application September 27, 1952, Serial No. 311,871

7 Claims. (Cl. 206—46)

This invention relates to cushioning pads and to the art of making and utilizing the same particularly in the packaging of fragile articles in a container for protection against damage from shocks and jars in transportation or handling in storage.

One object of the invention is to provide cushioning pads made of a material of extremely low density and light specific gravity, such as so called rubberized curled hair or equivalent spot bonded filaments, in which the interlocked filaments are so directed in relation to the pad surfaces that the sparse filamentary substance of the material suffices without reinforcement to perform an unusually efficient cushioning function.

A further object is to utilize in my improved pad rubberized curled hair that has been prefabricated in the form of a continuous straight edged thickish sheeting, web or strip, whereby to avoid the cost of molding rubberized hair into specially shaped bodies to serve as cushioning pads.

A further object is to establish a controlled degree of density in a cushioning body derived from a thick web of rubberized curled hair material by coiling a long strip of such material in convolutions into a spirally wound roll having flat broadside faces composed of the edges of the coiled strip, whereby the tightness with which the strip is coiled can determine the density of the material of the roll that is to be used as a cushioning body.

A further object is to so orient the spot bonded, interlocked filaments of the filamentary material in relation to the flat surface of the roll as to provide a maximum resistance to compression of the thickness of the roll, or cushioning pad, for a material of its composition and density wherefore a cushioning performance of unusual efficiency is obtained.

A further object is to so arrange improved cushioning pads, made of rolled stock as above described, in space between rigid walls of a shipping or storage container and a fragile article to be "floated" in such space, that the pad or pads fill such space in a manner to present one flat face of the roll toward or against the container wall and its other flat face toward or against the load chamber occupied by the fragile article.

A still further object is to combine the above said cushioning pads in a container with cushioning pads of other types having a like cushioning property of similar characteristic.

The foregoing and other advantages of the invention will appear in greater detail from the following description of successful embodiments of the present improvements having reference to the appended drawings wherein:

Fig. 1 is a perspective view showing in exploded relation packaging supplies for practising the invention including a shipping container with its cover and cover fastening means, a load article, and space filling cushioning bodies.

Fig. 2 shows the packaging elements of Fig. 1 as

2

sembled into a complete and closed shipping package embodying the invention.

Fig. 3 is a graph explanatory of advantages of the invention.

Fig. 4 is a perspective view of a cushioning body cut from a web of elongate resilient curly filaments interlocked and spot bonded together in accordance with this invention.

Fig. 5 illustrates a different form of shipping package 10 incorporating the invention with the outer wall of the container partially broken away to expose a load article packed by a practical use of my improved cushioning structure.

Fig. 6 is a view taken in section on the plane 6—6 15 in Fig. 5 looking in the direction of the arrows.

Fig. 7 shows a cylindrical container with its wall broken away to expose a still different arrangement of package cushioning construction embodying the invention.

Fig. 8 is an exploded view of the cushioning bodies 20 removed from the container of Fig. 7.

In most cushioning applications the primary function of cushioning material is not only to keep the contents of a shipping container from shaking around therein 25 but is also to absorb energy created by impact against the supporting frame or container or by violent acceleration or deceleration of the load to which the material is subjected. Resulting compression of the cushioning material should reduce such energy to a force less than that 30 which can safely be tolerated by the cushioned contents or load article.

Properties of packaging material that are desirable 35 include sufficient resilience in the cushioning body of the material to insure its full return to original dimensions after being repeatedly compressed, good damping capacity in the sense of sufficient reluctance to rebound too abruptly in recovering from its compression, and the ability to absorb a high proportion of the aforementioned energy generated by impact under a given relationship of load weight to the resulting compressional deflection of the cushioning body.

An important property of cushioning material is its 40 compression resistance. Compression resistances vary both in magnitude and in efficiency for various types and densities of cushioning materials, so that judicious selection of the material with the correct values for each 45 of these variations is the basis of cushioning design. For any type of material, the magnitude of compression resistance varies directly with the density but the efficiency usually varies with the type of cushioning material.

Whereas the concept of magnitude of compression 50 resistance expressed as pounds per square inch at a certain resulting deflection expressed as inches or percent of original thickness is readily understood, the concept 55 of efficiency, being of equal importance, should be further clarified by examples. An undamped spring obeying Hooke's Law has a linear compression resistance rate in which doubling the load doubles the deflection, tripling the load triples the deflection, and so on to the 60 limits of the spring. At any combination of load and deflection, the work done on the spring is $\frac{1}{2}$ of the product of load and deflection whereas ideally the work could be the product of the load times the deflection; thus the efficiency of work or energy storage is 50%.

Efficiency is readily determined for any cushioning 65 material by plotting the increasing increments of load as ordinates, and the resulting deflections of the material as abscissæ to obtain a compression resistance characteristic as represented in Fig. 3. Since the area enclosed by the curve, the X-axis and the abscissa for the desired deflection, represents the work done on the

cushioning when compressed to the desired deflection, efficiency may be computed by dividing this area by the maximum work obtainable which equals the product of the load times the deflection. Curve 46 in Fig. 3, representing a typical cushioning material, would have an efficiency of approximately 25% at 60% deflection because only 4½ of the possible 3×6 or 18 squares are under the curve 46.

Commercially available cushioning materials as heretofore used are generally less than 50% efficient. However, with a filamentary body so constructed that the majority of its filaments are oriented perpendicular to the face of the body that is subject to loading, most of the filaments will act as individual columns under compression in that they will offer a high initial resistance until they buckle and bow or bend individually. Following this, large deflections will occur for small additional increments of load. The result is a compression characteristic enclosing more than 50% of the possible chart area under the graph line. The compression resistance curve would become similar to curve 47 in Fig. 3 and which, by the method described in the preceding paragraphs, has an efficiency of 70%. This results in highly efficient bulk cushioning material.

In the web, sheet or strip of rubberized hair from which I propose to form a cushioning pad by coiling it into a roll, the direction of fiber lengths is mainly parallel with the surface of the face of the sheet material which are to become curved surfaces in the roll rather than perpendicular or normal to such surfaces. This disposes the lengths of the fibers or filaments into directions mainly paralleling the axis of the roll.

According to the broad principles above outlined there may be fabricated and used as cushioning material a yieldable body or bodies such as those designated 12 in Figs. 1 and 2. Each of these bodies has broadside faces 14 joined by crosswise extending edge surfaces 16 and 16'. The material as best shown in Fig. 4 comprises intermingled elongate resilient curled fibers or filaments interlocked by spot bonding them together in a manner to orient and maintain the filaments in such positions that their lengths extend mainly in directions more nearly parallel with said broadside faces 14 of the body than with the edge surfaces 16 thereof, as represented in Fig. 4. The fibers or filaments can to advantage constitute curled animal hairs, such as horse tail or horse mane, interlocked by bonding together at separated spots their respective coatings of vulcanized latex applied so sparsely that spacious unclogged spaces or voids permeate the material making room for free individual flexing of the filaments therein.

By arranging elongate spot bonded filaments in stratified disposition mainly and approximately in parallel relationship to the broadside surfaces of a cushioning body as aforesaid, and by disposing such cushioning body so that its edge surfaces toward which the filament ends are mainly directed, rather than its broadside faces, are respectively constrained by the wall of the shipping container 17 and presented toward the load article, greatly increased protection of the load article results with use of a cushioning material of reduced weight and lowered cost.

I prefer to produce such material initially in the form of a continuous thick sheeting or web which may be done by a fabrication method explained in greater detail in U.S. Patent No. 2,580,202. Such method tends strongly to orient and maintain the filaments positioned with their lengths extending in directions more nearly parallel with the top and bottom surfaces of the web than in directions crosswise the thickness of the web. Specifically I prefer to cut the aforesaid cushioning bodies from the aforesaid web. The broadside faces 14 of the former will be the residuum of the original top and bottom surfaces of the web. The peripheral

edge surfaces 16 of the cushioning bodies will be of shape to conform to the inside of the container wall. I then cut openings 18 through a plurality of such cushioning bodies and stack the bodies with their broadside faces together forming a laminate assembly in which the openings through the individual cushioning bodies are bounded by the inner edge surfaces 16' of the bodies and combine to form a hollow, load nesting space within which a load article can be lodged and resiliently constrained. The inner edge surfaces 16', rather than the broadside faces 14 of the bodies, face such load nesting space and impart to the load article in diminished magnitude whatever shock forces are derived at the outer edge surfaces 16 from the wall of the container, such forces being transmitted to the load article through the sparse filamentary structure of the cushioning bodies 12 and causing the filaments to flex mainly in response to forces of columnar compression.

In Figs. 1 and 2 the load article comprises a delicate instrument 20 fixed on a base plate 22. The assembly of the particular instrument and base plate herein shown calls for a nesting shape of load chamber 18 which may be bluntly triangular in horizontal cross section so that the edge surfaces 16' of the cushioning bodies 14 abut the load article all about to constrain it resiliently in all lateral directions.

In Figs. 1 and 2 there is shown a special adaptation of this invention embodied in a roll 24 made by coiling a narrow strip of the aforesaid web material in convolutions with the broadside faces 26 of the original strip wound progressively upon themselves with sufficient tightness to compress the normal thickness of the strip in each convolution to selective degree thereby to increase the density of the cushioning substance throughout the roll. The exposed edge surfaces 28 fall flush so that they combine to form flat broadside faces of the roll.

When so coiled into a roll with a selective degree of tightness the outer end 30 of the coil strip can be cemented or stapled or sewed to the underlying convolution thus to anchor it against uncoiling movement. This will preserve whatever degree of compression is originally set up in the filamentary material of the strip by maintaining the tightness with which the strip was pulled in winding it when originally coiled. Need for use of an adhesive along any continuous extent of the overlapping surfaces of the spiral convolutions is thereby eliminated because each convolution tightly imprisons all convolutions internal thereof thus placing the entire length of the coiled strip under self squeezed compression.

Of prime importance is the fact that this method of fabrication using a resilient, compressible prevulcanized material such as rubberized curled hair will produce pads of density that is mechanically determined and mechanically maintained by various degrees of compression resistance greater than that of the original prevulcanized material which is of constant density. The control over the density of the rolled pad depends entirely on the length of the strip used to produce the final pad, the thickness and density of the strip, and the final diameter of the rolled pad which is determined by the tightness of rolling. A pictorial comparison of the compression resistance of pads of various densities rolled from various length strips of the original material is represented by graphs 47, 48 and 49 in Fig. 3.

Having formed a roll of rubberized hair as described and recalling that the ends of the hair are presented toward the flat broadside faces 28 of the roll, I have found that the roll is capable of serving very efficiently as a cushioning pad by inserting it between the container 17 and the chamber containing load article 20, 22 as shown in Fig. 2. A pad like 24 can thus be used at the top and bottom of container 17 after which the conventional cover 32 can be applied and fastened in place by the removable split retaining ring 34.

In Fig. 5 a scheme of packaging is shown wherein pads such as 24 serve as the sole space filling material between the flat faced load article 36 and the flat walls 38 of a box-like container. In this instance the pads 24 will be cemented, stapled or otherwise fixed in position against the container walls 38 and will be somewhat compressed against the load article when the sides of the container are nailed together.

In Figs. 7 and 8 a cylindrical container 40 is seen equipped to cushion the load article 42, which may be a glass vial or the like, by use of pads like 24 at the top and bottom of the container, while the axially intervening space in the container is filled with a laminate of discs such as 12 cut radially into separate adjoining pie-shaped pieces 44.

A comparison of the increased efficiency in safe and effective cushioning performance resulting from this invention as compared with former practices in the art is fairly represented by the pictorial symbols in the chart of Fig. 3. Here the ordinates, or vertical distances on the chart to the various graphs 46, 47, 48 and 49 from the zero abscissa or base line A—A, are proportional to increments of increase of weight or compressive force of load in pounds per square inch exerted on cushioning bodies of basically similar composition when such bodies are variously positioned and conditioned between container wall and load article. The abscissa or horizontal distances to the same graphs from the zero ordinate or upright line 0—0 are proportional to corresponding increments of increase of deflection of the cushioning material in terms of percentage decrease of original dimension of the cushioning body in the direction the load force is applied, which direction as indicated by arrows F is assumed to be downward.

In the case of a disc 12, or laminate of such discs whether or not divided into sections like the pieces 44, disposed as represented on the chart the particular kind of cushioning material herein concerned yields too readily to initial increases in load force (F) acting against the broadside face of the pad as represented by graph 46. This results in poor cushioning action because of inability to absorb shock effectively until the cushioning body or bodies become compressed to say a half of their original unloaded vertical dimension. In contrast, a cushioning pad of the same overall size and shape constructed like the roll 24 does not yield with anywhere near the readiness responsively to initial increases in load force (F). As a result good cushioning action immediately comes into play to oppose initial increase of load force throughout even the first 20% deflection of the cushioning body. In the chart the amount of shock energy which the diverse arrangements of filaments in cushioning bodies 44 and 24 can effectively absorb is represented by the entire area that fills the space between each of the graphs 46 or 47 and the base line or zero abscissa A—A. Thus much more desirable shock absorbing action can be performed by the roll 24 than by discs 44 in opposition to load forces acting in the direction of arrows F.

When the roll 24 is wound more and more tightly upon itself the graph 47 may become more like graphs 48 and 49, showing that increase in the unloaded density of the cushioning material does not change the desirable characteristics of cushioning performance evidenced by graph 47. Concrete values of the increasing load force magnitudes and of the resulting increases of compressive deflection are marked on the chart for convenience of reference and without intention of thereby limiting the scope of the claims to this invention. They indicate values within a range of load force intensities that is practical in package cushioning by use of the material and arrangements herein involved.

One advantage of the rolled pad embodiment of the invention is that it constrains the filaments in a manner to resist their tendency to deflect laterally and buckle when subjected to columnar or endwise load thrust. Side

sway in the cushioning body is thereby inhibited and the performance of the cushioning body becomes more stable and dependable. The rolled strip form of cushioning body is also found to damp out initial shock impulses in a manner to inhibit repetitive rebound thus reducing the extent of vibration to which the load article is subjected.

As a different way of attaining these objectives, strip stock such as herein shown coiled into the roll 24 may instead be folded back and forth upon itself in successive plies which can be pressed together by stitching through the plies to preestablish compression of material in a pad so composed or in a laminate of relatively overlapping but unfolded pieces of the strip stock when so stitched together.

15 As a nonlimiting example of packages sizes in which the invention can to advantage be embodied the container of Figs. 1 and 2 may measure 16 $\frac{5}{8}$ " high by 10 $\frac{1}{2}$ " in diameter with a load article size of 8 $\frac{1}{2}$ " by 4" by 4 $\frac{1}{16}$ " weighing 2.81 pounds. The roll 24 may measure 4 $\frac{1}{16}$ " thick by 10 $\frac{1}{8}$ " overall diameter and weigh 0.40 pound. The laminate of side pads 12 may measure 8 $\frac{1}{2}$ " high by 10 $\frac{1}{8}$ " in overall diameter and contain a cutout 3 $\frac{3}{8}$ " by 4". The roll may be round, oval, or rectangular.

20 25 Pads comprising a roll or rolls made as herein explained serve the advantages explained in numerous uses aside from packaging such as in use as upholstery filler, rugs and rug underlays, vehicle mats, marine fenders, crash pads, shoe soles or platforms, etc.

30 35 Many variations in and departures from the shapes, proportions and arrangement of parts herein chosen to illustrate the principles of the invention can be resorted to for practicing such principles, wherefore the appended claims are directed to and intended to cover all substitutes and equivalents that fairly come within the broadest interpretation of the combination defined by the claims.

I claim:

1. In shock absorptive packaging, a cushioning pad 40 comprising a coiled strip of open filamentary material wound upon itself about an axis to form a roll, said material incorporating a sparsely intersticed network of mutually entangled long resilient filaments, each having a thin all-over coating of a vulcanized dispersion of elastomer bonding said filaments together only at spots of mutual contact or close proximity in such relationship that a preponderance of said filaments have their lengths oriented in directions paralleling said axis of the roll, and said coiled strip being wound upon itself with sufficient tightness to compress the inner coils of the said roll thereby to cause the said spot bonded filaments to bow individually in the said interstices of the said network of the said material.

2. In shock absorptive packaging, a cushioning pad as defined in claim 1, together with means fastening only the outer coil of the said roll to an underlying coil of said roll wherefore to maintain said tightness.

3. In shock absorptive packaging, a cushioning pad comprising a straight-edged coiled strip of filamentary material wound directly upon itself without interliner in a plurality of convolutions about an axis to form a roll of less thickness than its axial length in which the straight strip edges of adjacent convolution are substantially flush and combine to form opposite broadside surfaces of 60 65 the pad lying perpendicular to said axis, said material comprising a sparsely intersticed network of mutually entangled long resilient filaments, each having a thin all-over coating of a vulcanized dispersion of elastomer bonding said filaments together only at spots of mutual contact or close proximity and in such relationship that a preponderance of said filaments have their lengths oriented in directions paralleling said axis of the roll.

4. A shock absorptive compressible resilient cushioning pad comprising a roll having opposite ends forming flat parallel surfaces adapted to bear the compressive

forces of a load, said roll being formed by a strip of material composed of a self-coherent sparsely intersticed network of mutually entangled long resilient filaments each having a thin all-over coating of a vulcanized dispersion of elastomer bonding said filaments together only at spots of mutual contact or close proximity, and said strip being wound closely upon itself about an axis in a plurality of convolutions mutually having direct surface-to-surface contact, the edges of said strip lying mutually flush to form and dispose said flat parallel load bearing surfaces of said roll in perpendicular relation to said axis, the said filaments having a preponderance of their lengths oriented in directions more nearly parallel with said axis than with said load bearing surfaces.

5. In shock absorptive packaging, a cushioning pad comprising a straight-edged coiled strip of filamentary material wound directly upon itself without interliner in a plurality of convolutions about an axis to form a roll of less thickness than its axial length in which roll the straight strip edges of adjacent convolution are substantially flush and combine to form opposite broadside surfaces of the pad lying perpendicular to said axis, said material comprising a sparsely intersticed network of mutually entangled long resilient filaments, each having a thin all-over coating of a vulcanized dispersion of elastomer bonding said filaments together only at spots of mutual contact or close proximity and in such relationship that a preponderance of said filaments have their lengths oriented in directions paralleling said axis of the roll, together with a container housing said pad and a load chamber and having a rigid wall flanking one broadside surface of said pad on the opposite side of said pad from said load chamber while the opposite broadside surface of said pad borders on said load chamber, whereby a load occupying said chamber is separated from said container wall by the said thickness of said roll so that shock forces transmitted through the thickness of said roll between said load chamber and said container wall act in the said direction in which a preponderance of the lengths of the said filaments are oriented.

6. The combination defined in claim 5, together with a

load article in the said chamber, and space filling bodies of the same kind of filamentary material of which the said coiled strips are composed interposed between said load article and a related wall of the said container other than the said rigid wall, said bodies having their spot bonded filaments so oriented that a preponderance of the lengths of said filaments extend in directions normal to said related wall of the container.

7. The method of predetermining and maintaining a selective degree of density and cushioning resistance in a discal shaped pad of highly compressible rubberized hair which includes the steps of, producing a flexible strip of spot bonded rubberized hair of substantially uniform skeletal density having a width equal to the desired thickness of the pad, coiling a selected length of said strip into a plurality of overlapping convolutions with sufficient tightness of winding of said strip upon itself to compress the rubberized hair and reduce the thickness of the coiled strip thereby to form a roll having a thickness equal to the width of said strip and having a cushioning strength predetermined by the degree of tightness with which said strip is wound upon itself, and securing an outer convolution of said roll to an underlying convolution of said roll in a manner to maintain the said tightness.
